UNITED STATES PATENT OFFICE

SAMUEL N. GOODMAN, OF PHILADELPHIA, PENNSYLVANIA, ASSIGNOR TO CONYERS BUTTON AND MARTIN L. FINCKEL, OF SAME PLACE.

DESIGN FOR A KNITTED FABRIC.

SPECIFICATION forming part of Design No. 18,672, dated October 9, 1888.

Application filed August 13, 1888. Serial No. 252,648. Term of patent 3½ years.

To all whom it may concern:

Be it known that I, SAMUEL N. GOODMAN, a citizen of the United States, and a resident of Philadelphia, Pennsylvania, have invented a new and original Design for a Knitted Fabric, of which the following is a specification.

My design is fully shown in the accompanying drawing.

The design comprises parallel rows *a b* of small figures of the character shown in the drawing, the figures of each row being at an angle in respect to the longitudinal line of the row, and the figures of adjoining rows being at reverse angles and being staggered—that is

to say, the figures of one row occupying a position between the figures of the adjoining rows.

I claim—

The design for a knitted fabric, substantially as described, and as shown in the accompanying drawing.

In testimony whereof I have signed my name to this specification in the presence of two subscribing witnesses.

SAMUEL N. GOODMAN.
